METHOD AND APPARATUS FOR FORMING CORDS

Hans Alwin Schrenk, Arnhem, Netherlands, assignor to American Enka Corporation, Enka, N.C., a corporation of Delaware

Application April 14, 1954, Serial No. 423,168

Claims priority, application Netherlands April 27, 1953

4 Claims. (Cl. 57—58.3)

This invention relates to cording of threads and more particularly to a method and apparatus for cording in which the desired cord twist can be achieved in a single continuous cording operation irrespective of the starting twist of the component threads.

In the cording arts, it has been proposed that a device of the type shown in Patents 2,343,535, 2,442,775 and 2,503,242 be used. These are called one spindle cording devices because the threads from two packages are simultaneously unwound and corded about the axis of a single spindle. In order to obtain a desired cord twist from one of these one spindle cording devices, it is necessary that the component yarns or threads have such an initial twist that the additive effect imparted by the spindle will produce the desired result. Accordingly, if one wishes to produce from a one spindle cording device a cord having a construction of 10Z/10S starting from two threads each having a twist of 2Z, it has heretofore been necessary first to bring the twist of the two starting threads to zero by means of two separate 2S twisting operations and then to begin the cording on the one spindle device to produce a cord having 10 turns per inch in the S direction. Such a cord is referred to in the tire industry as having a 10Z/10S construction, by which it is ordinarily meant that the cord is composed of two singles originally having a twist of 10Z which have been twisted into a 10S cord. Stated differently, 10Z/10S cord construction, in the generally accepted definition of the term, means that the cord has ten S-turns per inch twist and that the individual singles actually have zero turns per inch twist as they appear in cord form. In reducing the cord twist to zero, however, ten turns in the Z direction will be added to each single. It is seen from this that although the singles possess no actual twist when lying in this particular cord construction, there is a theoretical or potential singles twist of ten turns per inch in the direction opposite to that of the cord twist, or Z-direction, from which emanates the designation accepted in the trade as 10Z/10S. However, as will be more apparent hereinafter, this same terminology may be used to designate cords produced in one continuous operation without prior twisting of the singles separately. Since pot spun rayon yarn is inherently possessed of twist of a few turns per inch, it is apparent that the preparation of rayon yarn for cording can and often does consume as much time as the cording itself.

It is an object of this invention to overcome the disadvantages of the prior art and to provide a method and apparatus to produce in a single, uninterrupted operation a cord of any desired twist construction from starting threads or singles of any twist.

According to the present invention, cord issuing from a one spindle cording device is fed directly and continuously to a twisting device such as a ring twister disposed in a cord twisting zone and the resulting cord is collected on the twisting spindle.

Other objects and advantages of this invention will be

2

apparent from the following detailed description of an embodiment thereof in conjunction with the annexed drawings, the single figure of which shows a typical arrangement in operating condition.

Referring now to the drawings in greater detail, the left side of the figure represents a one spindle cording device and the right side represents a cord twisting zone wherein the cord produced by the one spindle cording device may be further twisted by means of a ring twister.

5 The one spindle cording device per se shown is more fully described in co-pending application Serial No. 364,174, filed June 25, 1953. Yarns or threads from the packages 1 and 2 are corded and the resulting cord is led through the traveller 25 of the reciprocating ring 15 to be laid up on the twister package 30. Note that the thread 3 coming from the package 1 is led through a guiding eye 11 and an adjustable tensioning device 12 to a guide 13. From the guide 13 the thread 3 travels through a hollow spindle 14 which is mounted for rotation by conventional means and which is propelled by a driving pulley 15 driven by a belt 15a. Integral with the hollow spindle 14 is a disk 16 having therein a radial passageway 17 through which the thread 3 passes. The thread 3 freely balloons after leaving a disk 18 which 20 is connected to the disk 16. The balloon terminates at a point 5 where the thread 3 is corded with the thread 4 issuing from the package 2. The resulting cord passes through a thread guide 7 and then through guiding rollers 21 and 22 to the cord twisting zone wherein a guiding eye 23 is disposed above the ring twister.

The thread package 2 is mounted coaxially above the package 1 on a stationary part 19. There is a transparent protecting hood 20 mounted on the stationary part 19 surrounding the package 2 and affording visual access thereto. A thread guide 8 is disposed in the top of the hood 20 and axially above it are tension device 9 and thread guiding eye 10 which act upon the thread 4 in its movement toward the junction point 5. By any convenient arrangement the guiding eye 10 and/or the thread guide 7 are made vertically adjustable so that the position of the junction point 5 in relation to the guides is predetermined. It has been found that the build of the combined thread product is less satisfactory when the junction point 5 migrates too close to either of the thread guides 7 or 10. To prevent this unsatisfactory condition, tension devices 9 and 12 and thread guides 7 and 10 are relatively adjusted so that the junction point 5 is properly located.

40 If the pretension on the thread 3 decreases, the balloon tends to lead the disk 16 and in so doing a higher twist and a larger angle of twist result in the cord. This quickly decreases the height of the balloon to restore symmetry in accordance with the new pitch angle. By the same token, if the pretension of the balloon portion of the thread 3 increases, the balloon temporarily becomes higher with a smaller angle of pitch in the cord 6.

45 The cord 6 after leaving the guide 23 and passing under the traveller 25 is laid up in the form of a package on the twisting spindle 27. The twisting spindle is driven by a belt 29 through a pulley 28. Numeral 26a represents a fragment of the spindle twisting frame.

50 While the invention is illustrated with the cord being collected on a ring twister, a ring doubler, a cap twister or other twisting devices may be employed.

55 As an illustration of the method of the present invention, two examples are given as follows:

Example I

It was desired to manufacture a cord of twist formula 12Z/12S, from pot-spun singles, each having a twist of 2Z. Formerly, these individual singles would have been given a twist of 2S in order to neutralize the 2Z production twist, after which the singles would have been

corded, in a separate operation, on a one spindle cording device producing a cord twist of twelve **S**-turns per inch. Although the singles actually would have zero twist because of the additive effect of **2Z** and **2S**, the cord construction is referred to as **12Z/12S** because of the singles twist which would inherently result upon unwinding or unplying of the cord. It is difficult to perform these separate operations continuously.

According to the method of the present invention the **2Z** pot spun yarn mentioned was initially corded on the one spindle cording device with a cord twist of **10S**, continuously followed by an additional cord twist of **2S** on a ring twister, thus producing a **12Z/12S** cord construction in one single operation, as will next be explained.

When the **2Z** singles were plied on the single spindle cording device with a **10S** twist, a cord having the construction of **12Z/10S** was obtained, which means that the cord has a positive twist of ten turns per inch in the **S** direction, and the singles a potential or theoretical twist of twelve turns per inch in the **Z** direction. In arriving at this figure, it should be remembered that the **10S** twist added to the cord on a one spindle cording machine produces a potential twist of **10Z** in the singles (as explained hereinabove) which, when added to the **2Z** originally present in the singles, results in the **12Z** construction mentioned, although the actual twist in the singles is only **2Z**. Subsequent collection of this cord on a ring twister imparting additional cord twist does not, however, affect twist in the individual singles, as measured on a conventional twist tester. Consequently, adding a cord twist of **2S** by the ring twister collector increases the **10S** twist in the cord to **12S** but has no effect on the **12Z** singles twist, which results in the **12Z/12S** construction desired. By the use of the present invention, it can be seen that a cord construction of **12Z/12S** was produced in one continuous operation from singles having a production twist of **2Z**.

Example II

In this example, it was desired to manufacture an unbalanced cord construction of **12Z/10S** from untwisted singles in one continuous operation. Cord was produced in accordance with the present invention by plying the untwisted singles with **12S** twist on a one spindle cording machine. This produced a cord twist of **12S** and a potential singles twist of **12Z**, although the actual twist in the singles was zero. This cord was next collected on a ring twister imparting an additional cord twist of **2Z**. The additional twist was in the direction opposite from the original cording twist and the cord twist was reduced from **12S** to **10S**, although the singles twist was unaffected for reasons mentioned earlier. Although the theory behind this phenomena is not completely understood, actual tests on a conventional twist tester prove that collecting cord on a ring twister imparting further twist, in either direction, to the cord has no effect on the amount of actual twist present in the singles when the cord is unwound or unplied. Thus, starting with zero twist singles, a cord construction of **12Z/10S** resulted from the continuous operation described.

In this way any cord construction, complying with con-

sumers' demands, can be made continuously, starting from any twist condition of the elements from which the cord is to be made.

While a preferred embodiment of the invention has been described, it is to be understood that changes and variations may be made without departing from the spirit and scope of the invention as defined by the following claims.

What is claimed is:

1. A method for cording threads that comprises drawing a first thread from a package, rotating a second thread around the first to form a cord, continuously withdrawing the cord to a cord twisting zone and turning the cord about its axis and laying up the same in package form in the cord twisting zone.

2. A method for cording threads that comprises drawing a first thread from a first package, guiding said first thread between two points in a substantially vertical path co-axially above said first package, guiding a second thread from a second package, ballooning succeeding portions of said second thread about said first package to form a cord, continuously withdrawing the cord to a cord twisting zone and further twisting the cord during the formation of a package in the cord twisting zone.

3. Apparatus for the continuous manufacture of a thread product comprising in combination, means to rotate a first thread element about a second thread element at a point of joining to form a cord, means to continuously withdraw a cord from said point of joining to a cord twisting zone, and means in said cord twisting zone to turn said twisted cord about its axis to collect the same in package form.

4. Apparatus for the continuous formation of a cord comprising a first supply package mounted on a first stationary support, a second supply package mounted on a second stationary support, means to withdraw a first thread from said first supply package and to balloon it about said second supply package, means to guide a thread from said second supply package and combine the same with said first thread at a point of joining to form a cord, means to continuously withdraw said cord from said point of joining to a cord twisting zone, and twister means in said cord twisting zone to turn said cord about its axis and collect the same in package form.
